UNITED STATES PATENT OFFICE.

CHARLES W. HOLLENDER, OF PARIS, TEXAS.

ECCENTRIC.

SPECIFICATION forming part of Letters Patent No. 710,865, dated October 7, 1902.

Application filed January 8, 1902. Serial No. 88,926. (No model.)

To all whom it may concern:

Be it known that I, CHARLES W. HOLLENDER, a citizen of the United States, residing at Paris, in the county of Lamar and State of 5 Texas, have invented new and useful Improvements in Eccentrics, of which the following is a specification.

This invention relates to eccentrics, and the device is capable of efficient use in many 10 arts, although not being limited in this respect.

One advantageous employment of the eccentric is as a means for reciprocating the shakers of a bolting-machine, it being thus 15 disclosed in my contemporaneously pending application, Serial No. 78,894, filed October 16, 1901.

The improved eccentric includes a plurality of sections connected together to form a unitary article, and in the present case these sections are integral and are flanged, the flanges serving to prevent lateral motion of straps or like devices used in connection therewith, and one of the flanges is common to both eccentric-sections. Although any number of eccentric-sections may be employed, I have 25 simply shown two, this being for convenience.

The multiple eccentric carries an oil or lubricant receptacle, and conduits are provided for carrying the lubricant to the peripheries of the respective sections whereby easy running of the parts is assured. The receptacle for the lubricant may consist of an annular flange suitably fastened to one of the 30 faces of the eccentric and the oil may flow from the same by bores or passages opening into the receptacle and peripheries of the respective sections.

The invention is shown clearly in the accompanying drawings, forming a part of this specification, and in which—

Figure 1 is a plan view of a multiple eccentric including my improvements. Fig. 2 is a sectional side elevation of the same.

Like characters refer to like parts in both the figures.

I desire at this point to state that the invention is not limited to the exact construction shown in said drawings and hereinafter described in detail, for many changes may be made within the scope of the claims following this description.

The duplex eccentric is denoted in a general way by 5, and it is shown as having the oppositely-disposed sections 6 and 7 arranged 55 in superposed order. The eccentric is bored its entire depth, as at 8, to receive a shaft or similar element, or the said eccentric may be otherwise mounted, and it will be understood that the portions 6 and 7 are each eccentric 60 with respect to such bore 8 and each in itself constitutes an eccentric and is capable of being surrounded by a strap or its equivalent. While the sections 6 and 7 are shown as one located above the other, this construction being 65 adopted when the eccentric moves about a vertical axis, this is not essential, for they will be otherwise disposed when the eccentric moves about a horizontal or axis oblique thereto. The eccentric is flanged, as at 9, 10, and 11, the 70 flanges being annular and serving to limit the side play of eccentric-straps that operate in connection with said eccentric, and the intermediate flange 10 is common to both sections 6 and 7. The eccentric is furnished with 75 means for effecting the lubrication of the peripheries of the sections 6 and 7 thereof, and hence the adjacent surfaces of the straps and the lubricant can also pass onto the inner surfaces of the flanges 8, 9, and 10, respectively. 80 The lubricating means includes a receptacle, as 12, which is shown as consisting of an annular cup or flange open at the top to facilitate the introduction of a lubricant thereto, though this arrangement would not be followed where the eccentric turns about a horizontal axis. The receptacle or cup is circularly flanged at its base, as at 13, and screws or analogous means can pass through perforations in such flange and be tapped into what 85 is shown as the topmost flange 11. Conduits, as 14 and 15, are suitably bored or otherwise formed in the body of the eccentric and lead from and open into the receptacle or cup 12, the conduit 15, shown at the right, being 90 shorter than the conduit 14. These conduits are shown as being angular, what is represented as the lower branches being horizontal and opening into the peripheries of the sections 6 and 7. The oil supplied to the receptacle 12 flows therefrom into the open outer or upper ends of the conduits 14 and 15 and passing along the same will flow therefrom and onto the peripheries of the sections 6 and 95 100

7, so as to lubricate the latter, and consequently the flanges 9, 10, and 11. Naturally the straps encircling said sections 6 and 7 will be also lubricated. The flanges 9, 10, and 11 are shown as being formed in one piece with the sections 6 and 7.

Having described the invention, what I claim is—

1. A multiple eccentric, the sections of which are flanged and one of the flanges being common to two eccentric-sections, an oil-cup having a flange fastened to one of the other flanges and conduits leading from said cup to the respective sections.

15 2. A multiple flanged eccentric having conduits in the body thereof open at their opposite ends the outlets of the conduits being located in the peripheries of the respective

sections between the flanges thereof, and an oil-receptacle common to the inlets of said 20 conduits.

3. A multiple flanged eccentric having conduits in the body thereof open at their opposite ends the outlets of the conduits being located in the peripheries of the respective 25 sections between the flanges thereof and the inlets being located in the upper face of said eccentric.

In testimony whereof I have hereunto set my hand in presence of two subscribing witnesses.

CHARLES W. HOLLENDER.
